C. E. RENSHAW,
SUPERVISORY MECHANISM.
APPLICATION FILED JUNE 12, 1919.

1,407,819.

Patented Feb. 28, 1922.

Inventor
Charles E. Renshaw.

UNITED STATES PATENT OFFICE.

CHARLES E. RENSHAW, OF EAST ORANGE, NEW JERSEY, ASSIGNOR TO NEWMAN CLOCK COMPANY, INC., OF NEW YORK, N. Y., A CORPORATION OF NEW YORK.

SUPERVISORY MECHANISM.

1,407,819.

Specification of Letters Patent. Patented Feb. 28, 1922.

Application filed June 12, 1919. Serial No. 303,609.

To all whom it may concern:

Be it known that I, CHARLES E. RENSHAW, being a citizen of the United States, residing at East Orange, county of Essex, and State of New Jersey, have invented certain new and useful Improvements in Supervisory Mechanism, of which the following is a full, clear, and exact description.

Valves for controlling the flow of fluids are in such common use that they form a component part of practically every mechanical equipment in general use. Under certain conditions it is essential that they should remain open or remain closed at all times except for making repairs, extensions or for other recognized purposes; and it is a well recognized fact that loss of life and great damage has resulted through oversight or design in permitting valves to remain closed when their normal position should be open, and vice versa.

The invention which constitutes the subject matter of this application relates to supervisory mechanism, specifically described in connection with sprinkler systems. The use of automatic sprinkler systems is coming more and more into vogue, but like all other systems of water distribution the valves at times must necessarily be closed temporarily in order to effect repairs, to prevent freezing, and for many other purposes. There has been and is a tendency on the part of workmen to leave one or more of the valves closed, thereby putting a part or the whole of the system completely out of commission with a result of considerable losses in cases of fire.

My invention therefore has to do with mechanism adapted to be connected to a valve for controlling the access to a recording key located adjacent thereto. That is to say when the valve is open, as it normally should be, access may be had to the key, but if the valve is closed the key is not available. As each one of these valves (or "stations") is equipped with a key a time-print may be made on a record dial of a watchman's clock which would indicate the time at which the station was visited. So long as these imprints are made at the required intervals, as shown by the record dial, it is a sure indication that the valves at these particular times were opened. But if the imprint of a certain station were omitted from the record dial it would be an equally

sure indication that the key at that station was inaccessible and therefore the valve was closed. Of course, if it is a part of the watchman's duty to open the valve he could then make the imprint. In any event the device will have served its purpose.

Further objects and advantages will appear from the detailed description below taken in connection with the accompanying drawing, in which—

Fig. 1 is an elevation, partly in section, of a valve illustrating the invention in front elevation applied thereto.

Fig. 2 is a sectional side elevation of certain parts of the structure illustrated in Fig. 1.

Fig. 3 is a section taken on the line 3—3 of Fig. 2.

Referring to the drawing in detail, the reference numeral 10 designates the water supply to the sprinkler coming from any suitable pipe (not shown). Located in this supply is a valve 11 provided with a yoke 12, a threaded sleeve 13 rotatably mounted in the yoke, a valve-stem 14 screw-threaded to the sleeve, and a manipulating handle 15 fixed to the sleeve 13 and adapted to rotate the same in order to impart a longitudinal movement to the valve-stem 14 and the gate valve (not shown) attached thereto.

Fixedly mounted at any convenient location is a container or receptacle 1 in which a watchman's key, or other suitable record-producing means, 2 is mounted. The details of construction of this key need not be herein specified as the type of key described and claimed in the patent to Baldwin 1,238,706, or any of the other types known in the recording art, may be employed. The key 2 is preferably pivotally mounted at 3 within the receptacle 1 so as to be movable from a position within the same, as shown in full lines in Fig. 2, to a position partially outside the same, as shown in dotted lines in the same figure. A spring 4 secured at one end to a lug 5 in casing 1 and at its other end to an arm 6 secured to the key 2 constitutes a means for biasing said key to its outer or accessible position.

In order to render the key 2 inaccessible or inoperative, the following mechanism may be provided. The front of the receptacle 1, which is the only open side thereof, may be provided with vertical flanges 7 and detachable strips 8 to form a pair of ver-

tical grooves in which a sliding door 9 is adapted to travel. It will be seen that when the door 9 is elevated or open as indicated in dotted lines in Fig. 2 the key 2 is accessible and is moved to and held in the accessible or operative position by the spring 4. When the door is moved toward the closed or lower position the lower edge thereof engages the key 2 to move the latter to the inaccessible or inoperative position against the action of the spring 4. The lower front edge of the receptacle 1 may be flanged as indicated at 17 and provided with a detachable strip 18 to form a horizontal groove, similar to the above described vertical grooves, for the purpose of providing a more effective seal of the receptacle when the door is in closed position.

A plate 19 provided with a vertical slot 20 may be detachably secured to the receptacle 1 between the flanges 7 and 17 and the door 9 for the purpose of minimizing the chances of breakage of parts when the key 2 is in the operative position. The slot 20 is preferably made just large enough to clear the key and to permit the free movement of the latter from one position to the other. The plate 19 serves also as a means for preventing the introduction of any obstructions into the receptacle which might interfere with the operation.

In accordance with my invention connections are provided between the door 9 and a moving part of the valve to render the key 2 inoperative or inaccessible when the valve is closed either wholly or partially to any material extent. A simple form of such connections is illustrated in Figs. 1 and 2 and comprises an arm 25, secured at one end to the upper end of the valve spindle 14 and secured at its other end to a rod 26, in turn secured at its other end to the upper part of the door 9. The parts 25 and 26 may be made of any length, depending on the distance between the valve and the receptacle 1.

The design of parts is such that when the valve is in normal position the key is accessible or operative as shown in Fig. 1 and in dotted lines in Fig. 2. As the physical embodiment herein disclosed relates to a sprinkler system, the normal position of the valve is that in which it is open. If the valve has been closed a material amount and left in that position the door 9 will have been closed either entirely or partially. In either event the key 2 will be inoperative or inaccessible so far as effecting a record at that particular station is concerned.

If, on making his rounds, the watchman discovers that the key 2 is inaccessible he will know, if he is acquainted with the system, that the valve at that station is not entirely open. He will then open the valve, which operation will cause the key automatically to become accessible and he may then

make his record. If, because of ignorance, he does not realize the significance of the inaccessibility or inoperativeness of the key he will be unable to obtain a record at that station. Inspection of his record card will, however, show whether the valve at any particular station equipped with my invention was open or closed at any particular time. If the dial of the watchman's clock does not show a registration covering all of the valves which he is required to supervise it may readily be determined which valve or valves he had found not to be in normal position.

The construction illustrated and described is merely the preferred embodiment of my invention and it is to be understood that I do not limit myself thereto as it is obvious not only that many changes may be made in point of detail but other embodiments may be resorted to without departing from the true spirit and scope of my invention.

What I claim is:

1. In combination, a valve, a record producing key movable from an operative to an inoperative position and vice versa and biased to operative position, and means operatively connected to said valve for rendering said key inoperative when said valve is moved from normal position. 95.

2. In combination, a valve, a key movable from an operative to an inoperative position and vice versa and biased to accessible position, and means comprising a part operatively connected to said valve for rendering said key inaccessible when said valve is moved from normal position. 100

3. In combination, a valve, a key receptacle having a door, an operating element, and means for simultaneously opening said valve and door by moving said operating element. 105

4. In combination, a valve having a longitudinally movable stem, a stationary receptacle, a manually operable recording device within said receptacle, a closure for said receptacle, and means for causing said closure to be moved by and to the same extent as said stem. 110

5. In combination, a valve having a longitudinally movable stem, a stationary receptacle, a manually operable recording device within said receptacle, a sliding closure for said receptacle, and means for causing said closure to be moved by and to the same extent as said stem. 115

6. In combination, a valve, a key receptacle having a door, a key in said receptacle, means for simultaneously operating said valve and door and means for automatically projecting said key from its receptacle when said door is opened. 125

7. In combination, a valve, a key, means for moving said key to operative position whenever said valve is actuated in one di- 130

rection, and means for moving said key to inoperative position when said said valve is actuated in the opposite direction.

8. In combination, a valve, a stationary receptacle, a key pivotally mounted in said receptacle, a door for said receptacle, and means operatively connecting said door to said valve.

9. In combination, a valve, a key and receptacle therefor, resilient means connecting

said key to its receptacle, and means controlled by said valve for controlling access to said key.

10. A mechanism as specified in claim 1 in which a spring is employed to bias the key. 15

11. A mechanism as specified in claim 2 in which a spring is employed to bias the key.

In testimony whereof I hereunto affix my signature.

CHARLES E. RENSHAW.
